SHIPPING CONTAINER FOR ELECTRONIC APPARATUS OR THE LIKE

Francis X. Wojciechowski, Garden Grove, Calif., assignor to Hoffman Electronics, El Monte, Calif., a corporation of California

Filed May 22, 1964, Ser. No. 80,102

Term of patent 3½ years

(Cl. D58—11)

FIG. 7.

FIGURE 1 shows a top plan view of a shipping container for electronic apparatus or the like embodying my new design.

FIGURE 2 is an exploded side elevational view thereof rotated 90° from the position shown in FIGURE 1;

FIGURE 3 is an end elevational view taken along line 3—3 of FIGURE 1.

FIGURE 4 is an end elevational view taken along line 4—4 of FIGURE 2.

FIGURE 5 is an end elevational view taken along line 5—5 of FIGURE 2.

FIGURE 6 is an end elevational view taken along lines 6—6 of FIGURE 1.

FIGURE 7 is a perspective view of the shipping container for electronic apparatus or the like.

I claim:

The ornamental design for a shipping container for electronic apparatus or the like, substantially as shown.
